DESIGN FOR A COMBINED SACHET BALL AND HOLDERS THEREFOR

Jean E. Vivaudou, New York, N. Y.

Application January 27, 1941, Serial No. 98,416

Term of patent 3½ years

To all whom it may concern:

Be it known that I, Jean E. Vivaudou, a subject of Great Britain and resident of New York city, in the county of New York and State of New York, have invented a new, original, and ornamental Design for a Combined Sachet Ball and Holders Therefor, of which the following is a specification, reference being had to the accompanying drawing, forming a part thereof.

Fig. 1 is a side elevational view of a combined sachet ball and holders therefor, showing my new design.

Fig. 2 is a front elevational view of the same.
Fig. 3 is a rear elevational view of the same.

I claim:

The ornamental design for a combined sachet ball and holders therefor, as shown.

JEAN E. VIVAUDOU.
